UNITED STATES PATENT OFFICE.

DAVID MARTIN DE WITT, OF RUSSELLVILLE, ARKANSAS.

CARBURETER.

1,265,626.

Specification of Letters Patent.

Patented May 7, 1918.

Application filed October 6, 1916. Serial No. 124,070.

To all whom it may concern:

Be it known that I, DAVID M. DE WITT, a citizen of the United States, and a resident of Russellville, in the county of Pope 5 and State of Arkansas, have invented a new and Improved Carbureter, of which the following is a full, clear, and exact description.

My invention has for its object, to provide a carbureter having a vacuum chamber which is also the fuel chamber connected with a nozzle in a mixing chamber, there being a valve connection between the vacuum chamber and the outlet from the 15 mixing chamber, the valve of which is connected with a float in the vacuum chamber so that when the level of hydrocarbon in the vacuum chamber goes below normal, the valve will be opened by the downward movement of the float, and the suction at the outlet will reestablish the vacuum in the vacuum chamber to maintain the level of the hydrocarbon.

Additional objects of the invention will 20 appear in the following specification, in which the preferred form of the invention is disclosed.

In the drawings similar reference characters denote similar parts in all the views, 25 in which—

Figure 1 is a sectional elevation illustrating the construction of my carbureter; and

Fig. 2 is a sectional view on the line 2—2 30 35 of Fig. 2.

By referring to the drawings, it will be seen that the carbureter is provided with a casing 5 inclosing a vacuum chamber 6 and a suction pipe 7 provided with a transverse wall 8 forming the bottom of a mixing chamber, the suction pipe 7 having a conical wall 10 forming a nozzle at the top of the mixing chamber. Disposed in the mixing chamber 9 there is a nozzle 11 which is fed through an opening 12 in the transverse wall 8, there being another nozzle 13 disposed within the nozzle 11 which is fed from the vacuum chamber through an opening 14 in a pipe 15 which connects the member 5 with the suction pipe 7 and the nozzles 11 and 13. In the bottom of the nozzle 13 adjacent the opening 14 in the pipe 15, there is a needle valve seat 16, controlled by a needle valve 17, the said needle valve 17 having a thread 18 which meshes in a threaded opening 19 in an elbow 20

with which the suction pipe is provided. By this means the flow of hydrocarbon from the vacuum chamber 6 to the nozzle 13 may be regulated.

It will be understood that the hydrocarbon flowing out of the nozzle 13 will mix with the air flowing out of the nozzle 11, and that this mixture will pass out of the nozzle at the top of the mixing chamber 65 formed by the conical wall 10. The suction pipe 7 at the mixing chamber 9 has a branch 21, the end of which is threaded at 22, a cap 23 being provided with an inner thread 24 meshing with the thread 22. This 70 cap 23 has a valve seat 25, against which a valve 26 presses outwardly. This pressure is maintained by a spring 27 which engages the valve 26, the spring 27 being coiled around a spindle 28 having a head 75 29 with which the ends of the spring 27 engage. The spindle 28 is threaded at 30, this threaded portion meshing in a threaded opening 31 in a transverse member 32 secured to the cap 23. With this construction it will be understood that by turning the spindle 28 by its operating member 33, the head 29 on the spindle may be moved inwardly or outwardly, to regulate the tension of the spring 27. The tension of the 80 spring 27 may be adjusted, as has been stated, the function of the valve 26 being to automatically increase the supply of air in the mixing chamber 9 when the engine is running at high speed. There is a valve 90 95 34 in the suction pipe 7 to regulate the air which flows to the nozzle 11, and there is a valve 35 in the suction pipe 7 beyond the nozzle formed by the conical wall 10.

In the bottom of the casing 5 there is an 95 opening 36 around which there is secured a pipe 37 which extends upwardly in the vacuum chamber 6 a considerable distance. A hydrocarbon is fed to this pipe 37 through a pipe 38 which is connected with the bottom of the pipe 37 in any suitable manner, the hydrocarbon being drawn through the opening 14 to the nozzle 13 by the suction of the engine, and the hydrocarbon being replaced in the vacuum chamber by the 100 vacuum at the top thereof, which is formed with the withdrawal of the hydrocarbon to the nozzle 13. The top of the casing 5 is closed by a cap 39 which has an inner thread 40 meshing with an outer thread 41 on the 105 member 5. This serves to prevent the entrance of air into the vacuum chamber 6

under normal conditions, but in some cases air may enter the vacuum chamber 6, which will, of course, impair the working of the carbureter, since the hydrocarbon would 5 have to reach a very low level in the vacuum chamber 7 before the vacuum would draw into the vacuum chamber hydrocarbon through the pipe 37. To remedy this, I connect the casing 5 with the suction pipe 7 10 beyond the nozzle formed by the conical wall 10, with a pipe 42 having a valve seat 43 which is normally closed by a valve 44, the bottom of the valve 44 being hinged at 45. An arm 46 extends from the valve 44 adjust- 15 cent its hinge, this valve 44 having terminals 48 diverging at 47, the terminals 48 being articulated to projections 49 on a float 50. The float is preferably provided with a central opening 51 through which the pipe 37 ex- 20 tends.

In using the carbureter, the hydrocarbon which is drawn into the vacuum chamber 6 through the pipe 37 by the vacuum in the vacuum chamber, will be drawn through the 25 nozzle 13, and will be mixed with air drawn through the nozzle 11, the said mixture passing by the valve 35 to the engine. When the engine is running at very high speed an additional supply of air may flow into the 30 mixing chamber 9 through the valve seat 25. Should, at any time, the hydrocarbon in the vacuum chamber reach a low level the valve 44 will be opened, and the suction of the engine will draw air from the top of the 35 vacuum chamber 6, thereby producing the desired vacuum in the vacuum chamber 6, which will draw hydrocarbon through the pipe 37 and when this additional hydrocarbon in the vacuum chamber reaches a normal 40 level it will raise the float 50 to close the valve 44.

When the valve 44 is closed, the hydrocarbon feeds from the nozzle 13 under the suction of the engine which causes a vacuum or 45 partial vacuum at the top of the chamber 6.

It is understood that normally the valve 44 is closed and that it is only opened when the level of the hydrocarbon in the chamber falls below a predetermined point. When the valve 44 is opened, the pressure at the 50 top of the chamber is not further increased, but, on the contrary, the pressure at the top of the said chamber is reduced below a predetermined point, this being caused by the suction of the engine through the valve seat 55 43, and with this reduction of pressure at the top of the chamber 6, the hydrocarbon flows into the chamber 6 through the pipe 37 faster than it is fed at the nozzle 13, thereby raising the float 50 which closes the 60 valve 44. This prevents any further reduction of pressure at the top of the chamber 6, so that the hydrocarbon only flows into the chamber 6 through the pipe 37 as fast as it is fed at the nozzle 13. When the 65 hydrocarbon fails to flow into the chamber 6 as fast as it is used at the nozzle 13, the float 50 is again lowered, thereby opening the valve 44 and reducing the pressure at the top of the chamber 6, with the result 70 which has been described.

Having thus described my invention, I claim as new and desire to secure by Letters Patent:

A carbureter, comprising a suction tube 75 closed at its lower end, air and fuel nozzles in the said tube, the air nozzle opening through the closed end of the said tube, a spring pressed valve in the suction tube, a vacuum chamber adapted to contain a liquid 80 fuel and having at its lower portion a passage leading to the fuel nozzle and at its upper portion a passage leading to the suction tube, above the nozzles, a valve controlling the passage leading to the suction tube, 85 and means in said chamber for opening the valve controlling the passage leading to the suction tube when the fuel falls below a predetermined level.

DAVID MARTIN DE WIT.
